Int. Cl. D22—05

U.S. Cl. D22—13

FIG. 1 is a front isometric exploded perspective view of a combined fishing pole balancer and pivot stand therefor, showing my new design, the rear isometric perspective view being substantially identical in appearance;

FIG. 2 is a front elevational view, the rear elevational view being substantially identical in appearance;

FIG. 3 is a median, vertical, sectional view, the plane of the section being indicated by the line 3—3 in FIG. 2;

FIG. 4 is a top plan view showing the design as it appears when displaced somewhat from the geometrical central position illustrated in FIGS. 1-3; and

FIG. 5 is a bottom plan view of FIG. 4.

I claim:

The ornamental design for a combined fishing pole balancer and pivot stand therefor, as shown and described.
